CLAIM

The ornamental design for a display panel or portion thereof with a graphical user interface, as shown and described.

DESCRIPTION

FIG. 1 is a front view of a display panel or portion thereof with a graphical user interface showing a first embodiment of our design;

FIG. 2 is a front view of a display panel or portion thereof with a graphical user interface showing a second embodiment thereof;

FIG. 3 is a front view of a display panel or portion thereof with a graphical user interface showing a third embodiment thereof; and,

FIG. 4 is a front view of a display panel or portion thereof with a graphical user interface showing a fourth embodiment thereof.

The outermost broken line rectangle illustrates a display panel or portion thereof that forms no part of the claimed design.
